FRANCISZEK KLIMECZEK AND JACOB ZELEZNIAK, OF FILBERT, WEST VIRGINIA.

RAIL-JOINT.

1,098,909.

Specification of Letters Patent.

Patented June 2, 1914.

Application filed March 28, 1914. Serial No. 828,070.

To all whom it may concern:

Be it known that we, FRANCISZEK KLIMECZEK and JACOB ZELEZNIAK, subjects of the Emperor of Austria-Hungary, residing at Filbert, in the county of McDowell and State of West Virginia, have invented certain new and useful Improvements in Rail-Joints, of which the following is a specification, reference being had therein to the accompanying drawing.

This invention relates to rail joints and has for its object to provide means, in a manner as hereinafter set forth, for connecting together the opposing ends of a pair of track rails without the employment of nuts, at the same time allowing for the necessary contraction and expansion of the track rails due to climatic influences.

Further objects of the invention are to provide a rail joint which is comparatively simple in its construction and arrangement, strong, durable, efficient and convenient in its use, readily set up and inexpensive.

With the foregoing and other objects in view the invention consists of the novel construction, combination and arrangement of parts as hereinafter more fully described and illustrated in the accompanying drawings, wherein is shown an embodiment of the invention, but it is to be understood that changes, variations and modifications can be resorted to which come within the scope of the claims hereunto appended.

In describing the invention in detail reference is had to the accompanying drawings wherein like reference characters denote corresponding parts throughout the several views, and in which:—

Figure 1 is a side elevation of a pair of track rails, showing the adaptation therewith of a rail joint in accordance with this invention; Fig. 2 is a sectional plan of Fig. 1; Fig. 3 is a central transverse section of Fig. 1; Fig. 4 is a detail illustrating a portion of the locking plate; Fig. 5 is a detail illustrating a portion of one of the fish plates.

Referring to the drawings in detail, 6 and 7 denote a pair of track rails, and each includes a head 8, web 9 and base 10. Arranged at one side of the webs 9 and engaging the heads 8 and bases 10, is a fish plate 11, and arranged at the other side of the webs 9 and engaging the heads 8 and bases 10 is a fish plate 12.

The fish plate 11 is provided with a series

of square openings 13 arranged in alinement with circular openings 14 formed in the webs 9, and extending through the alining openings 13—14 are bolts, each including a head 15, and a shank having a squared portion 16 and a cylindrical portion 17, the latter having its periphery provided with oppositely disposed grooves 18. The heads 15 of the bolts abut against the outer face of the fish plate 11, the squared portions of the shanks of the bolts being seated in the openings 13, and the cylindrical portions 17 of the bolts projecting through the openings 14 and into the fish plate 12.

The fish plate 12 is provided with a series of longitudinally extending keyhole-shaped openings 19, and the contracted portion of each of said openings is indicated at 20. Each of the longitudinal walls of the contracted portion 20 of each of the openings is beveled in opposite directions as illustrated clearly in Fig. 3, and the said beveled walls are adapted to seat in the grooves 18 of the shanks of the bolts whereby lengthwise movement of the bolts is arrested. The cylindrical portions 17 of the shanks of the bolts are first entered in the enlarged portion of the keyhole-shaped openings 19, after which the fish plate 12 is shifted in a direction whereby the beveled walls of the contracted portion 20 of the keyhole-shaped openings will engage in the grooves 18 of the cylindrical portions 17 of the shanks of the bolts.

For maintaining the cylindrical portion 17 of the shanks of the bolts in the contracted portion 20 of the keyhole-shaped openings, retaining lugs 21 are employed, and which are so shaped as to allow of their being positioned not only in the enlarged portions of the keyhole-shaped openings, but to project into the contracted portion 20 of said keyhole-shaped openings and engage the cylindrical portions 17 of the shanks of the bolts, as clearly illustrated in dotted lines in Fig. 1, whereby the bolts are prevented from lengthwise movement, and the fish plate 12 from longitudinal movement upon the shanks of the bolts.

The retaining lugs 21 are carried by a plate 22 which is arranged against the outer face of the fish plate 12, and the said plate 22 is enlarged centrally as at 23, and formed centrally of its inner face, as at 24, with a pocket, and further provided centrally with an opening 25 having a round threaded wall.

Seated in the pocket 24 is a head 26 of a threaded member 27, the latter engaging with the threaded wall of the opening 25, and the said head 26 normally abutting 5 against the fish plate 12. The plate 22 is further provided with openings 28 which register with openings 29 formed in the fish plate 12. The walls of the openings 29 are threaded and engaging with the threads of 10 said walls are threaded inner ends 30 of bolts 31 which project through the openings 28 and outwardly with respect to the plate 22. The bolts 31 are provided with heads 32, and interposed between said heads and 15 the plate 22, and surrounding the bolts 31 are helical springs 33 which maintain the lugs or members 21 in the keyhole-shaped openings 19.

To release the bolts which extend through 20 the fish plate 11, webs 9 and into the fish plate 12, the threaded member 27 is revolved, which draws the plate 22 outwardly against the action of the spring 33. The member 27 is revolved until the lugs or members 25 21 are shifted clear of the openings 19, after which the fish plate 12 is shifted longitudinally, and in such direction that the grooved ends of the cylindrical portion 17 of the shank will be positioned into the enlarged 30 portion of the keyhole-shaped openings, and then the said bolts can be removed from the webs 9 and fish plate 11.

What we claim is:—

1. A rail joint comprising a pair of fish 35 plates adapted to be positioned against opposite sides of the webs of a pair of track rails, one of said fish plates having a series of openings and each opening of the series having an enlarged portion and a contracted 40 portion, the opposing walls of said contracted portions being oppositely beveled, bolts extending through the other of said fish plates and engaging in said openings and having grooves into which extend said beveled walls 45 to prevent lengthwise movement of said bolts, and means extending into said openings and engaging said bolts to prevent shifting upon said bolts of that fish plate provided with said openings, and a plate carrying said 50 means and connected with that fish plate provided with said openings.

2. A rail joint comprising a pair of fish plates adapted to be positioned against opposite sides of the webs of a pair of track rails, one of said fish plates having a series 55 of openings and each opening of the series having an enlarged portion and a contracted portion, the opposing walls of said contracted portions being oppositely beveled, bolts extending through the other of said fish 60 plates and engaging in said openings and having grooves into which extend said beveled walls to prevent lengthwise movement of said bolts, means extending into said openings and engaging said bolts to prevent 65 shifting upon said bolts of that fish plate provided with said openings, a plate carrying said means and connected with that fish plate provided with said openings, and resilient elements engaging said plate for 70 maintaining said means in said openings.

3. A rail joint comprising a pair of fish plates adapted to be positioned against opposite sides of the webs of a pair of track rails, one of said fish plates having a series 75 of openings and each opening of the series having an enlarged portion and a contracted portion, the opposing walls of said contracted portions being oppositely beveled, bolts extending through the other of said fish 80 plates and engaging in said openings and having grooves into which extend said beveled walls to prevent lengthwise movement of said bolts, means extending into said openings and engaging said bolts to prevent 85 shifting upon said bolts of that fish plate provided with said openings, a plate carrying said means and connected with that fish plate provided with said openings, resilient 90 elements engaging said plate for maintaining said means in said openings, and means for shifting said plate laterally to withdraw said means from said openings against the action of said resilient elements.

In testimony whereof we affix our signatures in the presence of two witnesses.

FRANCISZEK KLIMECZEK.
JACOB ZELEZNIAK.
